UNITED STATES PATENT OFFICE.

LAWRENCE F. OTTEN, OF NEWPORT, KENTUCKY.

BELT-BUCKLE.

1,393,721.

Specification of Letters Patent.

Patented Oct. 11, 1921.

Application filed March 14, 1921. Serial No. 451,976.

To all whom it may concern:

Be it known that I, LAWRENCE F. OTTEN, a citizen of the United States, residing in the city of Newport, in the county of Campbell and State of Kentucky, have invented certain new and useful Improvements in Belt-Buckles, of which the following is a specification.

My invention relates to belt buckles and 10 more particularly to those used upon belts for personal wear.

One of the objects of my invention is to provide a belt buckle of efficient and economical construction, which is adapted to 15 securely grasp and hold the belt upon the wearer at any point without the necessity of weakening the belt by perforations to receive the ordinary tongue of a buckle as heretofore made.

20 It is another object of my invention to so construct a belt buckle as to have a minimum of parts and yet to obtain a secure fastening of the belt.

It is another object of my invention to provide a buckle that is readily adapted to be 25 released with a minimum of movement on the part of the wearer and, at the same time, to make the releasing action positive so as to insure the release of the belt when desired.

30 My invention consists in providing a belt buckle having a minimum of parts readily adapted to secure the leading end of the belt and fasten it in place, and also to enable the wearer to easily release the end of the belt 35 in a positive manner with a minimum of movement and effort.

My invention further consists in the construction, combination and arrangement of parts as herein set forth and claimed.

40 In the drawing:

Figure 1 is a perspective view of the front side of my improved device applied to a belt.

Fig. 2 is a rear elevation of the same.

Fig. 3 is a horizontal section taken in a 45 plane corresponding to the line 3—3 of Fig. 2 and showing the parts in gripping relation.

Fig. 4 is a similar view, with the parts in released relation.

Fig. 5 is a vertical cross section taken in a 50 plane corresponding to the line 5—5 of Fig. 3.

Fig. 6 is a perspective view of the gripping member.

Fig. 7 is a perspective view of the operating member.

My improved buckle comprises a plate 10

which may be of any suitable shape. I have illustrated this plate formed with a rounded front for instance of convex form. The plate has integrally formed therewith slides 60 11 having inwardly turned lips 12. The inwardly turned lips, sides, and plate form a channel for positioning the free end 13 of the belt.

Upwardly turned ears 14 are formed on 65 the sides 11 adjacent one end of the plate. A pin 15 has its reduced ends 16 firmly secured in holes 17 of the ears, as by being riveted over as shown at 18. A gripping member 20 has a bearing 21 received about the pin 70 75 which may consist of a curl 22 integrally formed with the curved body 23 of the gripping member. The curvature of the body may be such as to follow the path of a circle whose center is distanced from the axis of the pin 15. The body of the gripping member has on its outer surface, teeth 25 having undercut surfaces 26 and upper sloping surfaces 27. Surfaces 26 and 27 merge in gripping points 28. The teeth are preferably inclined in a direction toward the outer lip 29 on the body of the gripping member. The body of the gripping member is preferably also curved in the direction of the axis of the bearing 21 thereon to conform to the shape 80 85 of the plate.

For actuating the gripping member, an actuating member 33 consists of a U shaped loop 34 having bearings 35 formed on the tangs 36 thereof received about the pin 15. 90

The tangs are connected by a cross piece 37. The bearings on the actuating member are journaled about the pin, between the upturned ears and the ends of the bearing 21 on the gripping member. The bearing on 95

the gripping member is preferably shorter than the body thereof. This permits the bearings 35 on the actuating member to occupy the space about the pin between the ends of the curl 22 and the side edges of the 100 gripping member. Thus the combined lengths of the bearings 21 and 35 are equal to the greatest width of the gripping member. Lugs 38 on the bearings 35 are adapted to contact stops 39 on the gripping member. 105

When the actuating member is in such position as to lie approximately in the plane of the belt, the lugs are spaced away from the stops on the gripping member so as to provide a certain amount of free movement of 110 the gripping member, when pressure is exerted by the wearer on the belt. When the

actuating member is moved at approximately right angles to the plane of the belt the lugs on the bearings contact the stops on the gripping members and disengage the 5 teeth thereon, from the free end of the belt and thus permit it to be released and withdrawn from the buckle.

For forcing the teeth of the gripping member into engagement with the belt when 10 it is desired to fasten the same, the tangs 36 of the actuating member contact stops 42 on the body of the gripping member. For securing the buckle to the belt, a loop 43 is formed on the end thereof by being passed 15 around the cross pipe 37 of the actuating member. The end of the loop may be secured by a snap fastener 44 to an intermediate portion of the belt. A retaining band 45 is secured to the belt to retain the free 20 end thereof extending beyond the end of the buckle.

When it is desired to fasten the belt, the free end is passed through the channel and under the gripping member, the actuating 25 member being held in the up position away from the buckle. In this position the lugs 38 on the actuating member 33 contact the stops 39 on the gripping member, thus holding a 30 it away from the plate 10 forming a space 48 to permit the uninterrupted passage of the free end of the belt. The end is then drawn to give the belt the desired 35 degree of tightness and the actuating member released. The pressure exerted by the wearer on the belt pulls down the actuating member, so as to force the tangs 36 into contact with the stops on the gripping member. This action forces the teeth into engagement 40 with the belt. The teeth being formed on the eccentric outline of the gripping member, tension on the belt will have the effect of forcing the teeth more firmly into the surface thereof and wedging it securely in place against unintentional release.

45 Should it be desired to release the free end from the buckle, the belt is grasped by the left hand adjacent the actuating member and pushed toward the buckle held in the right hand. This will rotate the actuating member about the pin, the lugs 38 thereon contacting the stops 39 on the gripping member and pulling the same out of engagement with the free end of the belt readily permitting it to be drawn out of 50 the buckle.

55 What I claim as new and useful and desire to secure by Letters Patent is:

1. In a belt buckle, a plate, a channel in said plate, a belt adapted to pass through 60 said channel, upturned ears on said plate,

a pivot on said ears, a serrated cam having movement about said pivot for engaging said belt, an actuating member separate from the gripping member having movement about said pivot adapted to selectively and positively force said cam into engagement with one portion of the said belt or disengage it therefrom, and means for attaching said actuating member to another portion of said belt.

2. In a belt buckle, a plate, upturned ears on said plate, a gripping member, a separate actuating member for said gripping member, a pin secured in said ears for combinedly pivoting said gripping member and said actuating member, a stop on the end of said gripping member, a lug on the end of said actuating member adapted to engage said stop on said gripping member for compelling combined movement of said members in one direction, and an additional stop on the end of said gripping member adapted to contact said actuating member for compelling combined movement in the other direction, the last named stop so placed as to be distanced from the actuating member when the first named stop is in contact with the said lug thereon.

3. In a belt buckle, a plate, a channel in said plate, a belt adapted to freely pass through said channel, upwardly turned ears on said plate, a pivot pin secured to said ears, a gripping member for gripping said belt comprising a sleeve bearing pivoted about said pin, a curved body whose outline is eccentric with reference to the axis of said bearing and whose width is relatively greater than the length of said sleeve bearing, stops on the ends of said body at the ends of said sleeve bearing, stops on the ends 90 of said body distanced from said first named stops, and teeth on the outer surface of said body inclined in a direction away from said bearing, a separate actuating member comprising a U shaped loop consisting of a cross 95 piece about which one end of said belt is adapted to be secured, and depending tangs formed on said cross piece adapted to coact with said second named stops to engage said gripping member with said belt where by it is secured in said channel, bearings on the ends of said tangs, and lugs on said bearings so placed as to coact with said first named stops to disengage said gripping member from said belt when said actuating 100 member is moved about said pin in a direction away from the plane of said plate, substantially as set forth and for the purpose specified.

LAWRENCE F. OTTEN.
